UNITED STATES PATENT OFFICE.

CHARLES W. DAKE, OF GRAND RAPIDS, MICHIGAN, ASSIGNOR TO THE DAKE-AMERICAN STEAM TURBINE COMPANY, OF GRAND RAPIDS, MICHIGAN, A CORPORATION OF MICHIGAN.

ELASTIC-FLUID TURBINE.

No. 880,365.

Specification of Letters Patent.

Patented Feb. 25, 1908.

Application filed March 22, 1906. Serial No. 307,460.

To all whom it may concern:

Be it known that I, CHARLES W. DAKE, a citizen of the United States, residing at Grand Rapids, in the county of Kent, State of Michigan, have invented certain new and useful Improvements in Elastic-Fluid Turbines, of which the following is a specification.

This invention relates to improvements in elastic fluid turbines, the improvements relating to the turbine itself rather than to the casing or nozzles and guide passages.

In the construction of turbines, owing to the high temperature at which the steam—the usual elastic fluid—is delivered, the rim of the turbine is unduly expanded beyond the central part, and consequently induces unnecessary strain at the periphery, and sometimes a tendency to warp. The strain of the expansion is also objectionable because of the increasing strain due to the centrifugal force occasioned by the high speed of the rotation usual in such engines.

The object of this invention is to provide a construction of turbine for use in such elastic fluid turbine engines, that shall obviate this difficulty.

I accomplish the objects of my invention by the devices and means described in the following specification.

The invention is clearly defined and pointed out in the claims.

A structure embodying the features of my invention is clearly illustrated in the accompanying drawing forming a part of this specification, in which—

Figure 1 shows an enlarged detail of a bucket section in place on a turbine disk, the sectional part being taken on a line corresponding to line $x-x$ of Fig. 2. Fig. 2 is a transverse sectional view through the rim of the turbine and the buckets thereon. Fig. 3 is a side elevation view of a complete turbine wheel with the buckets in place.

In the drawing, similar numerals of reference refer to similar parts throughout the several views.

Referring to the numbered parts of the drawing, the bucket sections 1 contain buckets 2 of the usual recurved type. These sections 1 are secured to the opposite sides of the disk 5 by means of bolts 3.

The periphery of the disk 5 is formed in dove-tailed shape in cross-section, with a broad portion towards the periphery and

circumferential shoulders at the narrow part. The shanks 4 of each of the segments 1, which fit into these shoulders, are securely clamped there by means of the bolts 3. An opening 7 is at the center for a shaft, and screw-holes 6 are provided for bolting the disk to a suitable flange on said shaft. The segments 1 are similar to each other and are arranged opposite each other, there being an open space between the ends of the segments 1 to 65 permit expansion, in the preferred form here illustrated. There are twelve segments on each face of the disk in this structure here illustrated. The space between the segments may be left entirely open as illustrated in Fig. 1; or an insulating material 8, such as hard fiber which is more or less elastic, may be placed between the segments to make the wheel continuous. This feature will be preferred in some instances. 75

I desire to remark that the particular form of securing the buckets is of particular advantage because it permits of the free expansion in the proper direction; but the feature of dividing the buckets up into segments in this way is of advantage with other means of attachment to the disk. 80

Having thus described my invention, what I claim as new and desire to secure by Letters Patent, is:

1. In an elastic fluid turbine, the combination of the disk 5; oppositely-faced segments 11 thereon, secured to the periphery of the said disk which is formed dovetailed to receive the same by suitable bolts therethrough, the said segments being separated from each other at their ends, and elastic insulating material arranged between said segments, co-acting for the purpose specified. 90

2. In an elastic fluid turbine engine, the combination with the turbine disk of bucket segments secured to the periphery thereof, which segments are separated from each other in relation to permit of independent expansion of the segments, and elastic insulating material arranged between said segments, co-acting as specified. 95

In witness whereof, I have hereunto set my hand and seal in the presence of two witnesses.

CHARLES W. DAKE. [L. S.]
